UNITED STATES PATENT OFFICE.

ROBERT HARTWIG, OF LOS ANGELES, CALIFORNIA.

COMBINED SUIT SUPPORT AND PRESSING DEVICE.

Application filed April 15, 1922. Serial No. 553,301.

To all whom it may concern:

Be it known that I, ROBERT HARTWIG, a citizen of the United States, residing at Los Angeles, in the county of Los Angeles and 5 State of California, have invented new and useful Improvements in Combined Suit Supports and Pressing Devices, of which the following is a specification.

This invention relates to a combined suit 10 support and pressing device.

An object of the present invention is to provide a device which will concurrently serve for the purpose of supporting and pressing coats and trousers of a suit. It 15 is also an object to provide a device for pressing pieces of wearing apparel, such for instance as neckties, and which is constructed and arranged to be attached to the suit pressing means if desired.

20 A further object is to provide a suit pressing means of extremely simple and substantial construction and which can be readily arranged in effective pressing position and from which the clothes may be 25 readily removed when desired.

One embodiment of the invention is herein described and illustrated in the accompanying drawings, in which—

Figure 1 is a front elevation of a device 30 showing a coat and a pair of trousers in dotted lines applied to the device and arranged in the pressing condition.

Fig. 2 is a detail cross section through one of the pressure applying structures.

35 Fig. 3 is a side elevation of the arm pressing members in effective position.

Preferably, my invention embodies a shoulder piece 2 to be disposed within the shoulders of a coat for instance of a suit 40 of clothes, and through this shoulder support is arranged a shank 3 which is preferably provided at its upper end with a hook 4 to engage any suitable primary support. The lower end of the shank 3 is also provided with a hook 5 to receive a pressing device to be explained hereinafter for pressing trousers. Adjacent the upper end of the shank there is provided a cross piece 6 constituting a hanger or support, the ends 45 of which are shown upturned as at 7. The cross piece 6 is spaced above the shoulder member 2 a suitable distance so as to provide for the arrangement of the collar and shoulders of a coat below the cross piece 6.

55 Pressing means are supported upon the

ends of the cross piece 6 to engage and compress the sleeves of the coat which are indicated at S in dotted lines. The sleeve pressing means includes an outer panel 10 of suitable material and having a plane inner surface which is preferably covered with a soft or pad like material, which may consist of a layer of felt 11. The outer panel of the sleeve pressing means 11 is of elongated form and of sufficient width to 60 practically cover the sleeve below the arm pit, on one side, and the upper end of this member is provided with any suitable device for suspending it from the cross piece 6. Such device may consist of a single loop 70 or bight of strap or cord like material 12 so that the outer panel 10 can be independently supported. Opposed to the inside of the panel 10 is an inside sleeve pressing panel 13 of substantially similar form to 75 the outer panel except that the upper end of the inside panel 13 is cut away as at 13' to pass up under the arm pit of the sleeve. This enables the two panels 10 and 13 to be adjusted upon the inside and outside of 80 the sleeve and well up toward the shoulder of the sleeve, so that when the panels are firmly pressed together the sleeve will be neatly pressed and have folds or seams along its front and rear portions. 85

To secure the desired pressure upon the inclosed sleeve, a simple device is shown as consisting of a resilient arm 15 passing around the outer side of the outer panel 10 and carrying a thumb screw 16 in its free end and upon which is mounted a swiveled bottom 17 shown in section in Fig. 2. The opposite end of the resilient arm 15 is provided with a flattened lug 15' perforated to receive a pivot screw 18 upon which is 90 mounted a wing nut 19. The screw 18 passes through a lug 20 opposed to the lug 15' and is provided on the rear end of an arm 21 which may be of strap iron extending across and secured to the inside panel 100 13. The strap iron 21 therefore forms a transverse brace across the panel and also forms a support for the screw 18 about which may be swung or adjusted the resilient pressure producing arm 15. After the 105 sleeve has been embraced between panels 10 and 13, the desired pressure is secured by swinging the arm 15 across the outer panel 10 and then turning the thumb screw 16 so as to press the swivel bottom 17 against 110

the outside of the panel which may be reinforced as by a strap iron 10'.

Each of the sleeve pressing panels is provided with a suspending device 12 as above

5 mentioned, and there is a pair of the sleeve pressing devices incorporated in the apparatus so that each of the sleeves of a coat can be pressed simultaneously in respective pressing devices.

10 For pressing the trousers of a suit of clothes, there is provided a pair of complementary and substantially co-extensive presser members, one of which is indicated at 22 and the other at 23, and these are each 15 provided at their upper ends with separate and independent hooks 24 to be passed into the hook or eye portion 5 at the lower end of the shank 3 of the support. This enables the suspension of the two presser panels 22 and 20 23 loosely from the hook 5 so that a pair of trousers as indicated at T in dotted lines can be introduced therebetween, and then a pressure arm 15, of which a suitable number is 25 provided can be swung upwardly from the dotted line position, Fig. 1, to the full line position to enable the adjustment of the thumb screws 16 to secure the desired pressure. It is understood that the trouser pressing panels 22 and 23 are provided with pressure effecting means 21 and 15 as above 30 described with relation to the sleeve pressing device.

The improved pressing means including the complementary panel members of a given 35 set obviously can be constructed and arranged and designed for the effective pressing of other articles of wearing apparel, such for instance as neckties, etc., which can be readily introduced between the co-ordinate panels and the pressure brought to bear 40 by the adjustment of the thumb screw 16 of the respective pressure arms 15.

From the above it will be seen that the 45 panel members of each pressing device are substantially independent of each other and they may be readily separated to permit the insertion of a piece of apparel to be pressed by the dislocation of the respective resilient pressure arms 15. After the article to be 50 pressed is inserted, the arms 15 are swung into position transversely across the pressing panel and then the thumb screw 16 is set up to press the one member toward the other while embracing the article.

55 Various changes and modifications may be made without departing from the spirit of the invention as claimed.

What is claimed is:

1. A device for pressing pliant pieces of 60 wearing apparel comprising a pair of panel members of substantially co-extensive form in outline and between which may be disposed the article to be pressed, and a resilient element connected to one of the panels and 65 adapted to be transversely adjusted across

the other panel and carrying an adjustable part for pressing the opposed panels one against the other.

2. A device for pressing pliant wearing apparel and comprising a panel member 70 having at one side a part provided with a pivot member, a resilient arm mounted upon said pivot member, and a second panel adapted to be disposed opposite the first panel and across which the resilient arm is 75 adapted to be arranged transversely, said arm carrying an adjustable part for pressing one panel against the other.

3. A device for pressing pliant articles of 80 wearing apparel and comprising a pair of relatively disconnected pressure panels, and a plurality of resilient pressure arms pivotally connected to one of said panels and adapted to be adjusted across the outside of the other panel for pressing one of the panels 85 toward the other.

4. A device for pressing pliant articles of 90 wearing apparel and comprising a pair of relatively disconnected pressure panels, a plurality of resilient pressure arms pivotally connected to one of said panels and 95 adapted to be adjusted across the outside of the other panel for pressing one of the panels toward the other, and means for regulating the degree of pressure of one panel on the other.

5. Apparel pressing means comprising a 100 pair of opposed panel like members of substantially similar form, and means for pressing one of the panels toward the other upon the interposed piece of apparel, each of the panel members being provided on its effective pressing face with a pad like cover and 105 said means for pressing comprising a resilient arm extending over one panel and secured at its end remote from said panel to a strap which is rigidly connected with the other panel.

6. A suit pressing apparatus comprising in 110 combination, a shoulder piece upon which the shoulders of a coat may be arranged, a transverse carrying member connected to and spaced above the shoulder piece, and sleeve pressing means connected to and suspended 115 from the ends of the transverse carrying member and adapted to respectively embrace and press a sleeve at each side of the coat.

7. A suit pressing apparatus comprising 120 in combination, a shoulder piece upon which the shoulders of a coat may be arranged, a transverse carrying member connected to and spaced above the shoulder piece, sleeve 125 pressing means connected to and suspended from the ends of the transverse carrying member and adapted to respectively embrace and press a sleeve at each side of the coat, and means for pressing a pair of trousers; the several parts being combined to form a 130 suit pressing unit.

8. A suit pressing apparatus comprising a shank member adapted to be attached to a primary support, a carrying member attached to the shank, sleeve pressing means and support the same while the sleeve pressing means are applied, and a trouser pressing means attached to the lower end of the shank.
- 5 suspended from the ends of the carrying member, a shoulder piece spaced below the carrying member and mounted on the shank to receive the shoulders of an applied coat

In testimony whereof I have signed my name to this specification.

ROBERT HARTWIG.
